CLAIM

The ornamental design for a box vase, as shown and described.

DESCRIPTION

FIG. 1 is front perspective view of a box vase showing my new design;

FIG. 2 is a front elevational view thereof;

FIG. 3 is a rear elevational view thereof;

FIG. 4 is a right-side elevational view thereof, the left-side elevational view being a mirror image thereof;

FIG. 5 is a top plan view thereof;

FIG. 6 is a bottom plan view thereof; and,

FIG. 7 is a cross-sectional view taken along line 7—7 of FIG. 4.

The broken lines depict environmental subject matter only and form no part of the claimed design.

1 Claim, 4 Drawing Sheets
